SPOON FLY FISHING LURE

Malcom P. Holder, P.O. Box 420, Nice, Calif.

Filed Jan. 19, 1959, Ser. No. 54,212

Term of patent 7 years

(Cl. D31—4)

FIG. 1

FIG. 2

FIG. 3

FIG. 4

FIG. 1 is an enlarged perspective view of spoon fly fishing lure showing my new design;

FIG. 2 is a top plan view thereof;

FIG. 3 is a right side elevational view thereof; and

FIG. 4 is a front elevational view thereof.

I claim:

The ornamental design for a spoon fly fishing lure, as shown.
